(57) **CLAIM**

The ornamental design for a fishing rod flotation handle, as shown and described.

DESCRIPTION

FIG. 1 is a perspective view of the fishing rod flotation handle showing my new design, the subject matter shown in broken lines being for illustrative purposes only and forming no part of the claimed design;

FIG. 2 is a perspective view of the detached handle shown in FIG. 1.

FIG. 3 is a side elevation of the handle FIG. 2; and,

FIG. 4 is an end view of the handle of FIG. 2, the opposite end of which is a mirror image.
